UNITED STATES PATENT OFFICE.

HARRY H. VICKERS, OF CORONA, NEW YORK, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed January 26, 1921. Serial No. 439,941.

To all whom it may concern:

Be it known that I, HARRY H. VICKERS, a citizen of the United States, residing in Corona, Long Island, in the county of Queens and State of New York, have invented certain new and useful Improvements in Combined Typewriting and Computing Machines, of which the following is a specification.

10 This invention relates to error-preventing means for combined typewriting and computing machines, and is in the nature of an improvement on the application of Henry L. Pitman, Serial No. 418,913, filed October 15, 1920.

In machines of the Underwood-Hanson type, such as that disclosed in the above-mentioned application, index pins are set on denominational bars in accordance with the 20 numeral keys depressed, and the numbers so indexed are run into the register by a general operator which may be driven either manually or by motor. The motor of a motor-driven machine may be thrown into action 25 by a finger-piece near the front of the machine, or by one farther back, the latter also being actuatable automatically by suitable means. Such machines are adapted to perform either addition or subtraction. Whenever index pins are incorrectly set, it is desirable to restore such pins to normal position, and to effect a correct setting of index pins before actuating the general operator. Such restoration may be effected by means of 30 an elimination or error key, and suitable means rendered effective thereby. Also, in such machines, provision is usually made of a clearance or star key, which, when the register or numeral wheels stand at zero, may be 35 depressed to cause a star or other clearance sign to be printed on a work-sheet in the machine.

The main object of the invention is to provide simple and efficient means to prevent the 40 erroneous actuation of various keys at the same time and to prevent interference between the different parts of the machine when actuated.

Another object of the invention is to provide, for such purposes, mechanism easy and economical to manufacture and which may readily be applied to existing machines.

In carrying out the invention, provision may be made of means whereby depression 55 of the error key will prevent actuation of the

general operator by either the usual motor-starting key adjacent the keyboard or the slide through which the automatic starting of the motor is usually effected. The means just referred to may also be adapted to lock 60 the error key in case either the motor-starting key or the slide is actuated.

Provision may be made of means whereby depression of the error key will effect locking of the numeral keys, or depression of any 65 one of the numeral keys will effect locking of the error key.

Provision may be made of means whereby depression of the error key will prevent printing of a clearance sign by depression of 70 the clearance key.

Provision may be made whereby movement of the general operator from its normal position will cause the error key to be locked against depression.

Provision may also be made of means whereby depression of a numeral key will prevent actuation of the clearance-sign-printing mechanism by the clearance-key.

Further provision may be made whereby 80 depression of the usual motor-starting key will prevent the operation of any one of the numeral keys, or actuation of any one of the numeral keys will prevent the operation of said usual motor-starting key.

Other features and advantages will hereinafter appear.

In the accompanying drawings,

Figure 1 is a sectional side view, showing my invention applied to so much of an Underwood-Hanson typewriting and computing machine as is necessary for the purpose of illustration.

Figure 2 is a view partly in section, showing part of the mechanism whereby restoration to normal position of depressed index pins is effected when the error key is depressed.

Figure 3 is a fragmentary perspective view, showing the new structure.

Figure 4 is a view, showing certain of the parts in the positions assumed when a numeral key is depressed.

Figure 5 is a detail view, showing certain of the parts in the same positions as in Figure 4.

Figure 6 is a view, showing certain of the parts in the positions assumed when the motor-starting key near the front of the machine is depressed.

110

Figure 7 is a detail view, showing certain parts in the same positions as in Figure 6, the numeral keys being locked against depression.

Figure 8 is a view showing the positions assumed by certain parts upon depression of the error or elimination key, the numeral keys, the clearance-key, the motor-starting key and the motor-starting slide being locked against depression.

Figure 9 is a view illustrating the locking of the error key when the general operator has been moved from its normal position.

Figure 10 is a detail view showing the manner in which the numeral keys are locked, due to depression of the error key.

Upon actuation of a numeral key 11, a pendant or link 12 pivoted thereto, will act on an arm 13 to rock a shaft 14, on which said arm is fixed. Rocking of the shaft 14 effects, by means of an arm 15 secured thereon, a pin-setting movement of a linkage having a lower bar 16 adapted to set pins 17 on selected pin-bars or denominational members 18. It should be understood that there is one shaft 14 and one pin-setting linkage for each numeral key having a significant digit thereon.

The pins on said members 18 are normally to the rear of the paths of the bars 16, and are brought into position to be set thereby by suitable denomination-selecting means, which will cause the denominational members 18 to be advanced seriatim to positions to permit pin-setting. This denomination-selecting means may be substantially the same as that disclosed in the patent to Hart, No. 1,287,301, granted December 10, 1918, and comprises rods or thrust links 19, which, when actuated, will swing corresponding levers 20 about their pivots, and, by means of transposition linkages 21 and bell-crank 22 engaging pins 23 on the respective denominational members 18, advance the latter to pin-setting positions.

After a number has been indexed on the pins 17 of the proper pin-bars or denominational members 18, a motor-starting key 24 may be depressed against the action of a spring 25 to swing a lever 26 about its pivot 27 to depress the right-hand end of a lever 28, thereby lifting a motor-trip pin 29 and 30, releasing the motor, which, by means of a member 30 projecting into a yoke 31 on the general operator 32, will cause the latter to be reciprocated. Upon forward movement of the general operator, bar 33 constituting a part thereof will engage the depressed pins 17 and actuate the denominational members 18, and, therefore, register or numeral wheels 34 in accordance with the pins indexed, the result of the computation being read through a sight-opening 35.

During the return movement of the general operator, the pin-bars 18 will be restored to

their normal positions and the depressed pins will be reset in the usual manner. Actuation of the lever 28 to lift the motor-trip pin 29 may also be effected by means of a vertically movable slide or device 36, having a pin 37 thereon beneath the forwardly-extending arm of a lever 38, urged by a spring (not shown) to actuate said slide and normally held against such spring by means of a latch-member 39. The connections for starting the motor may be in general the same as those disclosed in the pending application of Carl E. Norin, Serial No. 309,836, filed July 10, 1919, (now Patent No. 1,370,475, dated March 1, 1921) and the motor controlled by the pin 29, as well as the connection between the motor and the general operator, may be substantially the same as in the patent to Alfred J. Wood, No. 1,299,646, granted April 8, 1919.

It should be understood that more than one register comprising wheels 34 may be provided, a set of pin-bars and denomination-selecting mechanism being associated with each register but the pin-setting linkages being common to all of the sets of pin-bars or denominational members 18.

Provision may be made of subtraction-setting mechanism similar, in general, to that disclosed in the patent to Minton, No. 1,280,065, dated September 24, 1918. As herein disclosed, the depression of a subtraction key 40 will move a link 41 against the resistance of a spring 42, and, by means of an arm 43, fixed on a shaft 44, rock the latter to withdraw a hook 45 from engagement with a shoulder 46 on a subtraction bar 47, permitting the latter to be drawn to the rear by a spring 48, connected thereto at one end and at the other end to a fixed part of the machine. Such movement of the subtraction bar 47 will effect, through a bell-crank 49 and an arm 50, connected to a bar 51 pivoted near its upper edge, rocking of bar 51, and consequently will shift the shafts 14 to change the connection between the arms 15 and the pin-setting linkages. As a result of this change, the shafts 14, when rocked, will activate the pin-setting linkages which are complementary to the base nine, to the linkages actuated thereby when the shafts 14 are in their normal positions. The rearward movement of subtraction bar 47 will also effect, through connections, not shown, depression of all of the "9" pins, by means of a bar 52. As is well known to those skilled in the art, the parts are now positioned to enable indexing a number for subtraction by the complementary method.

In case an error is made in indexing a number on pins 17, it may be desirable to restore all of the indexed pins to their normal positions, to enable the number to be indexed correctly. This may be done by de-

pressing an error or elimination key 53 against the action of a spring 54. The key 53, when depressed, rocks a member 55 about a shaft or pivot 56, and, by means of a link 57, attached at its forward end to an arm 58 on said member 55, and at its rear to a slide 59, moves said slide to the rear, against the action of a spring 59^a, and effects a restoration of the erroneously indexed pins to normal position by means similar to that disclosed in the patent to Wallseben, No. 1,255,828, dated February 5, 1918.

The pin-restoring platform 60 may be supported at each end by bell-cranks 61, those at the front being connected to those at the rear by means of a link or links 62, and downward movement of the pin-restoring platform being limited by means of an arm 63, movable with the forward bell-cranks 61 and engaging, when the pin-restoring platform is in its lowest position, a member 64 beneath the pin-restoring platform and connected thereto. The slide 59 is supported at its rear end by a pin 65, extending through a slot 66 in a bracket 67, mounted on a fixed part of the machine. When the slide 59 is moved to the rear, it will tension a spring 68, connected to the pin 65 and to the downwardly-extending arm of a bell-crank 69, pivoted at 70 on the bracket 67, and, as the slide 59 approaches the rearward limit of its movement, a pin 71 thereon will engage the downwardly-extending arm of a latching bell-crank 72, swinging the upper arm thereof out of the path of a stud 73 on the bell-crank 69, thereby releasing the latter to the action of the spring 68, which will swing the bell-crank 69 in counter-clockwise direction and cause its rearwardly-extending arm to engage a pin 74 on one of the rear bell-cranks 61, thereby effecting upward movement of the pin-restoring platform 60. The latching bell-crank is normally held in its effective position against a pin 75, by any suitable means, such as a spring.

As will be seen from inspection of Figure 2, the pin-restoring platform 60 is provided with downwardly-inclined ends, so that, in case the general operator is actuated when the pin-restoring platform is held in its upper position by the spring 68, the bar 33 of the general operator will cam the pin-restoring platform downwardly so as to pass thereover.

Before starting a new computation, it is customary to test the cleared condition of the machine by means of a star or clearance key 76. Such key 76, when depressed against the action of spring 54 corresponding to that associated with the error key 53, will actuate an arm 77 fixed on shaft 56, and thereby swing an arm or latch 78, fixed on said shaft, against the action of a spring

78^a, out of the path of a pin 79 on a link 80, to permit suitable means, such as a spring, to swing an arm 82, to which link 80 is connected, about a shaft or pivot 83, to actuate a star or clearance-sign-printing device. The counter-clockwise movement of arm 82 about the shaft 83 will cause, by means of a link 84, depression of a lever 85 corresponding in general to the numeral-key levers, and, by means of a usual bell-crank 86, swing a type-bar 87 about a pivot 88 to effect printing on a work-sheet on a platen (not shown) by means of star or clearance-sign types 89.

In order that the printing of the star or clearance sign may correctly indicate that the totalizer is cleared, it is usual to provide mechanism such as that disclosed in the patent to Hoyt, No. 1,256,309, dated February 12, 1918, whereby depression of the star key will be prevented unless all of the numeral wheels are set at zero. It will also be evident that all of the indexing pins 17 must be in their normal positions at the beginning of a computation. To that end, the member 55, normally actuated by the error key, has an offset portion 90, having at its right an ear 91 loosely embracing the shaft 56, and the offset portion 90 is provided with a lug 92 extending beneath the arm 77, so that depression of the star key 76 will effect swinging of member 55, and, consequently, an upward movement of the pin-restoring platform 60, to restore to normal position any of the index pins 17 which may be in depressed position. Printing of the star or clearance sign will, therefore, indicate that the machine is in condition to start a new computation.

The numeral keys 11 may then be depressed to index numbers, as hereinbefore described. In order to prevent the depression of more than one numeral key at a time, provision may be made of an intruding member 93 pivoted on each pendant 12, so that when any numeral key is depressed, the intruding member 93, connected therewith, will be projected between two of a set of pivotally-mounted crowding members or dogs 94, the movement of which is limited by suitable means, such as screws 95, so that only one of said intruding members 93 may be depressed at one time.

In carrying out the invention, the right-hand dog 94 is preferably provided with an arm 96 extending substantially horizontally from the pivot 97 of said dog. It will be evident that the weight of said arm tends to turn the dog 94, with which it is connected, in a clockwise direction, and, consequently, to crowd the dogs 94 to the left. When, however, any one of the numeral keys 11 is depressed, the right-hand dog 94 will be forced to the right to its limiting position in contact with screw 95, and the arm

96 will be lifted so as to enter a notch 98 in a link 99, extending through an aperture 100 in the plate 101 on which the crowding dogs 94 are mounted. The link 99 will then be locked against rearward movement, and, by means to be explained more fully hereinafter, will lock the error key 53 against depression. In its upward movement, the arm 96 will also lift the rear end of a lever 102 pivoted on shaft 83, and thereby effect movement of a latch-member 103, pivoted at 104, into engagement with a shoulder 105 on the motor-trip key 24 and thereby lock the latter against depression. The operative connection between the lever 102 and latch-member 103 may be effected by means of a pin 106 on the latter, projecting into a suitably-shaped cam-slot 107 in the forward end of the former. The latch-member 103 may also be provided with an arm 108 so shaped that, when the latch-member 103 is moved into locking position, the arm 108 will assume a position such as to obstruct the rearward movement of a pin 109 mounted on arm 78, and thereby prevent actuation of the latter by the star key 76, and, consequently, prevent operation of the star-printing mechanism. The latch-member 103 may normally be held in its ineffective position by means of a spring 110, connected at one end to a fixed part of the frame and at the other to said latch-member.

Upon depression of the error key 53 to restore any erroneously indexed pins 17 to normal position, a pin 111 on said key will engage an arm 112, fixed on a shaft 113, and lock the latter in a clockwise direction, as seen in Figure 1. In case of a plurality of registers, additional arms 112 may be fixed on shaft 113 so as to be actuatable by the pin 111 on the corresponding error key. By such rocking of the shaft 113, an arm 114 fixed thereon is swung to the rear and shifts rearwardly the link 99, the forward end of which is pivoted thereto at 115, so that the notch 98 in the link 99 is carried out of the path of the arm 96 on the right-hand dog 94, thereby preventing a lifting movement of said arm 96, by reason of the engagement of the lower edge of link 99 with the upper edge of said arm 96, and, consequently, locking the numeral keys against depression. The rearward movement of arm 114 will also effect, by means of a horizontal portion 116 thereof overlying the forward end of a lever 117, rocking of said lever 117 about the shaft 83 against the action of a spring 118. In such downward movement of the forward end of lever 117, a stud 119 thereon will engage the inclined front edge of the latch-member 103 and swing the same to the rear to engage the shoulder 105 on the motor-trip key 24, thereby locking the latter against depression. It will be evident also that the arm 108 will be rendered effective at the

same time to lock the star key 76 against depression. The lever 117 may be of such length that, when actuated by the error key, its rearward end will be raised into engagement with a projection 120 on the motor-trip slide or key 36, thereby preventing the actuation of the latter either manually or by the usual automatic means.

Whenever it is desired to throw the general operator into action, the motor-trip key 24 may be depressed, thereby bringing its front edge 121, above the shoulder 105 thereon, into engagement with the rear face of the latch-member 103, to lock the latter against rearward movement, and, consequently, to lock lever 102 and lever 117 against actuation by a numeral key or the error key, respectively. It will be seen also that the latch-member 103 will not be released by the key 24 until the latter has been returned to its normal position.

In case the slide 36 has been depressed to actuate the motor-trip mechanism, the projection 120 on said slide engages or is brought into proximity to the rearward end of lever 117 and will prevent actuation of the latter by the error key 53 as long as the slide is in its depressed position. As soon, however, as slide 36 is released, the error key may be depressed.

For reasons pointed out in said application of Henry L. Pitman, it is undesirable to permit actuation of the error key during the operation of the general operator or while the latter is out of its normal position. To that end, provision may be made of a hook 122, pivoted preferably on the same axis as the rearward bell-cranks 61, and having a rearwardly-extending arm 123 with an offset 124 normally in engagement with the lower face of a side bar 125 of the general operator 32, whereby the hook 122 will be maintained in ineffective position.

As the general operator 32 moves forward, the portion of the side bar 125 overlying the offset 124 will ride off the same, and permit the hook 122 to swing forwardly and engage the rearward end of the lever 117, thereby locking the error key against depression. Shifting of the hook 122 to release the lever 117 will not be effected until the general operator again approaches its original position, when the proper portion of the side bar 125 will ride over the offset 124 and restore the hook 122 to its normal ineffective position.

As herein disclosed, provision is made of the usual shaft 126 by which manual operation of the general operator may be effected in case the motor mechanism has been disconnected therefrom, the handle 127 for operating said shaft being indicated in dash lines on Figure 1. Driving connections between the shaft 126 and the general operator 32 may consist of pinions 128 meshing with

racks on the side bars of the general operator, and with toothed sectors 129 fixed on said shaft 126. The shaft 126 is utilized in controlling certain parts of the computing mechanism, irrespective of whether it actuates the general operator or is actuated thereby.

As herein disclosed, proper support of the rearward portion of link 99 is insured by providing a boss 130 on said shaft 126, 10 said boss having a cylindrical portion on which said link 99 may rest.

Variations may be resorted to within the scope of the invention, and portions of the improvements may be used without others.

15 Having thus described my invention, I claim:

1. In combination, computing mechanism comprising numeral keys for controlling the same, a clearance key, a clearance-sign- 20 printing mechanism controlled by said clearance key, and means whereby depression of any one of said numeral keys will prevent actuation of said printing mechanism.

2. In combination, computing mechanism comprising numeral keys for controlling the same, a clearance key, a clearance-sign- 25 printing mechanism normally urged to print, a latch normally restraining said printing mechanism, means whereby said clearance key may release said latch, and means whereby depression of any one of said numeral keys will prevent actuation of said latch by said clearance key.

3. In combination, computing mechanism comprising numeral keys for controlling the same, a clearance key, a clearance-sign- 35 printing mechanism normally urged to print, a latch normally restraining said printing mechanism, means whereby said clearance key may shift said latch to ineffective position, a device shiftable to a position to block movement of said latch, and means whereby depression of a numeral key 40 will cause movement of said device to effective position.

4. In combination, computing mechanism comprising numeral keys for controlling the same, a clearance key, a clearance-sign- 50 printing mechanism normally urged to print, a latch normally restraining said printing mechanism, means whereby said clearance key may shift said latch to ineffective position, a pivoted member shiftable to a position to block movement of said latch, and means whereby depression of a 55 numeral key will effect shifting of said pivoted member to effective position.

5. In combination, computing mechanism comprising numeral keys for controlling the same, a clearance key, a clearance-sign- 60 printing mechanism controlled by said clearance key, means whereby depression of any one of said numeral keys will cause the remaining numeral keys to be locked against depression, and means whereby the numeral-

key-locking means, when rendered effective by depression of any one of said numeral keys, will prevent printing by said printing mechanism.

6. In combination, computing mechanism 70 comprising numeral keys, devices in which numbers may be indexed in accordance with the numeral keys depressed, and a general operator whereby numbers so indexed may be computed, motor mechanism for actuating 75 said general operator, a motor-trip device, a motor-trip key for actuating said motor-trip device, and means whereby the depression of any one of said numeral keys will lock said motor-trip key against actua- 80 tion.

7. In combination, computing mechanism comprising numeral keys for controlling the same, a clearance key, a clearance-sign- 85 printing mechanism controlled by said clearance key, and means whereby depression of any one of said numeral keys will lock said clearance key against depression.

8. In combination, computing mechanism comprising numeral keys, devices in which 90 numbers may be indexed in accordance with the numeral keys depressed, and a general operator whereby numbers so indexed may be computed, motor-actuated means for actuating said general operator, a motor-trip device, a motor-trip key for actuating said motor-trip device, a clearance key, printing 95 mechanism controlled by said clearance key, and means whereby the depression of any one of the numeral keys will lock both said 100 motor-trip key and said clearance key against depression.

9. In combination, computing mechanism comprising numeral keys, devices in which 105 numbers may be indexed in accordance with the numeral keys depressed, and a general operator whereby numbers so indexed may be computed, an elimination key, elimination-key-actuated means whereby the index devices may be restored to normal condition, 110 and means whereby depression of any one of said numeral keys will effect locking of said elimination key.

10. In combination, computing mechanism comprising numeral keys, devices in which 115 numbers may be indexed in accordance with the numeral keys depressed, and a general operator whereby numbers so indexed may be computed, motor-actuated means for actuating said general operator, a motor-trip device, a motor-trip key for actuating said motor-trip device, a latch adapted to cooperate with said motor-trip key and lock the same against actuation, and means whereby the depression of any one of said 125 numeral keys will shift said latch to effective position.

11. In combination, computing mechanism comprising numeral keys, devices in which 130 numbers may be indexed in accordance with

the numeral keys depressed, and a general operator, whereby numbers so indexed may be computed, motor-actuated means for actuating said general operator, a motor-trip device, a motor-trip key for actuating said motor-trip device, a pivoted latch adapted to co-operate with said motor-trip key and lock the same against actuation, and means whereby the depression of any one of said numeral keys will cause said latch to be swung into effective position.

12. In combination, computing mechanism comprising numeral keys, devices in which numbers may be indexed in accordance with the numeral keys depressed, and a general operator whereby numbers so indexed may be computed, motor-actuated means for actuating said general operator, a motor-trip device, a motor-trip key for actuating said motor-trip device, a device made effective by the depression of any numeral key to prevent depression of any of the other numeral keys, and means whereby said preventing device, when rendered effective by any one of said numeral keys, will effect locking of said motor-trip key.

13. In combination, computing mechanism comprising numeral keys, devices in which numbers may be indexed in accordance with the numeral keys depressed, and a general operator whereby numbers so indexed may be computed, motor-actuated means for actuating said general operator, a motor-trip device, a motor-trip key for actuating said motor-trip device, a device made effective by the depression of any numeral key to prevent depression of any of the other numeral keys, a latch to co-operate with said motor-trip key and lock the same against actuation, and means whereby said preventing device, when made effective by any one of said numeral keys, will cause said latch to be shifted to effective position.

14. In combination, computing mechanism comprising numeral keys, devices in which numbers may be indexed in accordance with the numeral keys depressed, and a general operator whereby numbers so indexed may be computed, motor-actuated means for actuating said general operator, a motor-trip device, a motor-trip key for actuating said motor-trip device, a latch adapted to co-operate with said motor-trip key and lock the same against actuation, means to prevent the depression of more than one numeral key at a time, comprising intruding members actuatable by said numeral keys and crowding dogs having a limited movement so that only one of said intruding members may be inserted at one time, a member shiftable by one of the end dogs, and means whereby shifting of said member, due to actuation of a numeral key, will effect locking of said motor-trip key.

15. In combination, computing mechanism

comprising numeral keys, devices in which numbers may be indexed in accordance with the numeral keys depressed, and a general operator whereby numbers so indexed may be computed, means for actuating said general operator, including a starting key, and means whereby depression of any one of said numeral keys will effect locking of said starting key.

16. In combination, computing mechanism comprising numeral keys, devices in which numbers may be indexed in accordance with the numeral keys depressed, and a general operator whereby numbers so indexed may be computed, means for actuating said general operator, including a starting key, a member movable into position to co-operate with said starting key and prevent operation thereof, and means whereby depression of a numeral key will cause said member to be moved into effective position to lock said starting key.

17. In combination, computing mechanism comprising numeral keys, devices in which numbers may be indexed in accordance with the numeral keys depressed, and a general operator whereby numbers so indexed may be computed, means for actuating said general operator, including a starting key, a locking device whereby depression of any one of the numeral keys will prevent depression of any other numeral key, and means, actuated by said locking device, when the latter is made effective by the depression of a numeral key, for locking said starting key against actuation.

18. In combination, computing mechanism comprising numeral keys, devices in which numbers may be indexed in accordance with the numeral keys depressed, and a general operator whereby numbers so indexed may be computed, means for actuating said general operator, including a starting key, a latch-member movable into position to co-operate with said starting key and prevent operation thereof, means whereby depression of one of said numeral keys will lock the others, comprising intruding members actuatable by said numeral keys and crowding dogs having a limited movement so that only one of said intruding members may be inserted at one time, and means whereby insertion of one of said intruding members between the crowding dogs, due to depression of a numeral key, will effect movement of said latch-member to effective position.

19. In combination, computing mechanism comprising numeral keys, devices in which numbers may be indexed in accordance with the numeral keys depressed, and a general operator whereby numbers so indexed may be computed, means for actuating said general operator, including a starting key, a latch-member movable into position

- tion to co-operate with said starting key and prevent operation thereof, means whereby depression of one of said numeral keys will lock the others, comprising intruding members actuatable by said numeral keys and crowding dogs having a limited movement so that only one of said intruding members may be inserted at one time, a member shiftable by one of the end dogs, and means whereby shifting of said shiftable member, due to actuation of a numeral key, will move said latch-member to effect locking of said starting key.
20. In a combined typewriting and computing machine, in combination, computing mechanism including numeral wheels, numeral keys, devices in which digits may be indexed in accordance with the numeral keys depressed, and a general operator whereby numbers may be run into said numeral wheels in accordance with the indexing in said devices, a clearance key, a clearance-sign-printing device rendered effective by said clearance key, an elimination device for restoring said indexing devices to normal condition, an elimination key to control said elimination device, and means whereby depression of said elimination key will lock said clearance key.
21. In a computing machine, in combination, numeral keys, numeral-key-locking means including members connected with said keys, a set of locking dogs, and means to limit the movement of said dogs, so that only one of said members may be inserted between said dogs at any one time, an elimination key, and means whereby actuation of a numeral key will lock the elimination key, or operation of the elimination key will lock the numeral keys, comprising an arm carried by one of said dogs at one end of said set, and a longitudinally movable member actuatable by said elimination key, said member being provided with a notch adjacent to said arm whereby actuation of the dog carrying said arm will cause said arm to enter the notch and thereby lock said member and the elimination key against movement, or in case of actuation of the elimination key said member will be moved to carry said notch away from the path of said arm, thereby effecting locking of said arm and consequently of the numeral keys.
22. In a computing machine, in combination, numeral keys, numeral-key-locking means including members connected with said keys, a set of locking dogs, and means to limit the movement of said dogs, so that only one of said members may be inserted between said dogs at any one time, an elimination key, means whereby actuation of a numeral key will lock the elimination key, or operation of the elimination key will lock the numeral keys, comprising an arm carried by one of said locking dogs at one end
- of said set, a movable member normally positioned to co-operate with said arm, a starting key for said machine, means whereby depression of said starting key will lock said movable member, and, through said arm, render said dogs effective to prevent depression of said numeral keys, and means whereby actuation of said movable member due to depression of a numeral key will lock said starting key against actuation.
23. In a combined typewriting and computing machine, in combination, a clearance key, a clearance-sign-printing device normally urged to print, means including a latch controlled by the clearance key for maintaining said device in ineffective condition, computing mechanism, a member by which the actuation of said computing mechanism is started, and a member adapted when shifted to effective position to prevent movement of said latch to ineffective position, and to prevent movement of said starting member from its normal position.
24. In a combined typewriting and computing machine, in combination, a clearance key, a clearance-sign-printing device normally urged to print, means including a latch controlled by the clearance key for maintaining said device in ineffective condition, computing mechanism, a member by which the actuation of said computing mechanism is started, and a pivoted member adapted, when effectively positioned, to present an arm in position to engage a shoulder on said first-mentioned member, and another arm in the path of said latch to prevent movement of the latter to ineffective position.
25. In combination, computing mechanism comprising numeral keys for controlling the same, a clearance key, a clearance-sign-printing mechanism controlled by said clearance key, means whereby depression of any one of said numeral keys will cause the remaining numeral keys to be locked against depression, comprising intruding members actuatable by said numeral keys and crowding dogs having a limited movement so that only one of said intruding members may be inserted at one time, a member shiftable by one of the end dogs, and means whereby shifting of said shiftable member due to actuation of a numeral key will lock said clearance key.
26. In combination, computing mechanism comprising numeral keys, devices in which numbers may be indexed in accordance with the numeral keys depressed, and a general operator whereby numbers so indexed may be computed, an elimination key, elimination-key-actuated means whereby the index devices may be restored to normal condition, means whereby depression of any one of said numeral keys will effect locking of the others, comprising intruding members

actuable by said numeral keys and crowding dogs having a limited movement, so that only one of said intruding members may be inserted at one time, and a locking device including a member operable by said elimination key and a member shiftable by one of the end dogs upon depression of a numeral key to co-operate with said elimination-key-operated member to prevent actuation thereof, and thereby to lock the elimination key.

27. In combination, computing mechanism comprising numeral keys, devices in which numbers may be indexed in accordance with the numeral keys depressed, and a general operator whereby numbers so indexed may be computed, an elimination key, elimination-key-actuated means whereby the index devices may be restored to normal condition, means whereby depression of any one of said numeral keys will effect locking of the others, comprising intruding members actuable by said numeral keys and crowding dogs having a limited movement, so that only one of said intruding members may be inserted at one time, and a locking device including a member actuable by one of said end dogs when a numeral key is depressed, and a member movable by said elimination key, the arrangement and construction of said members being such that either one, when moved to actuated position, will prevent movement of the other.

28. In combination, computing mechanism comprising numeral keys, devices in which numbers may be indexed in accordance with the numeral keys depressed, and a general operator whereby numbers so indexed may be computed, an elimination key, elimination-key-actuated means whereby the index devices may be restored to normal condition, means whereby depression of any one of said numeral keys will effect locking of the others, comprising intruding members actuable by said numeral keys and crowding dogs having a limited movement so that only one of said intruding members may be inserted at one time, and a locking device including a member movable by said elimination key and a member movable by one of the end dogs, these two members being mounted to move in intersecting planes, one of said members being provided with a recess adapted to receive a portion of the other, movement of the first member, to carry the recess therein out of the path of the second, serving to lock the second, and movement of the second to cause said portion to enter the recess in the first serving to lock the first.

29. In combination, computing mechanism comprising devices in which numbers may be indexed and a general operator whereby numbers so indexed may be computed, actuating means for said general op-

erator, an elimination key, elimination-key-actuated means whereby the index devices may be restored to normal condition, a clearance key, a clearance-sign-printing mechanism controlled by said clearance key, and means whereby actuation of said elimination key will prevent actuation of said clearance key and also of said general operator.

30. In combination, computing mechanism comprising devices in which numbers may be indexed and a general operator whereby numbers so indexed may be computed, motor-actuated means for actuating said general operator, a motor-trip device, a member by which said motor-trip device may be operated, an elimination key, elimination-key-actuated means whereby the index devices may be restored to normal condition, a clearance key, a clearance-sign-printing mechanism controlled by said clearance key, and means whereby actuation of said elimination key will prevent operation of said motor-trip device by said member and will prevent actuation of said clearance key.

31. In combination, computing mechanism comprising devices in which numbers may be indexed and a general operator whereby numbers so indexed may be computed, motor-actuated means for actuating said general operator, a motor-trip device, a member by which said motor-trip device may be operated, a clearance key, a clearance-sign-printing mechanism controlled by said clearance key, an elimination key, and elimination-key-actuated means whereby the index devices may be restored to normal condition, including means for locking said member and said clearance key against movement.

32. In combination, computing mechanism comprising devices in which numbers may be indexed and a general operator whereby numbers so indexed may be computed, motor-actuated means for actuating said general operator, a motor-trip device, a member by which said motor-trip device may be operated, a clearance key, a clearance-sign-printing mechanism normally urged to print, clearance-key-controlled means normally holding said printing mechanism in ineffective condition, including a latch member, an elimination key, an elimination-key-actuated means whereby the index devices may be restored to normal condition, and a member controlled by said elimination key, so that upon operation of the elimination key, it will be moved into position to lock both said motor-trip member and said latch against movement.

33. In combination, computing mechanism comprising devices in which numbers may be indexed and a general operator whereby numbers so indexed may be computed, motor mechanism for actuating said

- general operator, a motor-trip device, a key to operate said motor-trip device directly, a second key, a lever actuatable by said second key and positioned to engage the motor-trip device to actuate the same, a clearance key, a clearance-sign-printing means controlled by said clearance key, an elimination key, and elimination-key-actuated means whereby the index devices may be restored to normal condition and both of the motor-trip keys and the clearance key locked against movement. 70
34. In combination, computing mechanism comprising numeral keys, devices in which numbers may be indexed in accordance with the numeral keys depressed, and a general operator whereby numbers so indexed may be computed, motor mechanism for actuating said general operator, a motor-trip key for rendering said motor mechanism effective, and means whereby depression of any one of said numeral keys will lock said motor-trip key against actuation, and depression of said motor-trip key will lock all of said numeral keys against depression. 80
35. In combination, computing mechanism comprising numeral keys, devices in which numbers may be indexed in accordance with the numeral keys depressed, and a general operator whereby numbers so indexed may be computed, motor mechanism for actuating said general operator, a motor-trip key to render said motor mechanism effective, a clearance key, printing mechanism controlled by said clearance key, and means whereby depression of any one of the numeral keys will lock both said motor-trip key and said clearance key against depression, and depression of said motor-trip key will lock all of said numeral keys and said clearance key against depression. 85
36. In combination, computing mechanism comprising numeral keys, devices in which numbers may be indexed in accordance with the numeral keys depressed, and a general operator whereby numbers so indexed may be computed, an elimination key, elimination-key-actuated means whereby the index devices may be restored to normal condition, and means whereby depression of any one of said numeral keys will effect locking of said elimination key, and depression of said elimination key will lock all of said numeral keys. 90
37. In combination, computing mechanism comprising numeral keys, devices in which numbers may be indexed in accordance with the numeral keys depressed, and a general operator whereby numbers so indexed may be computed, motor mechanism for actuating said general operator, a motor-trip key for controlling said motor mechanism, a latch adapted to co-operate with said motor-trip key and lock the same against actuation, and means whereby depression of 100
- any one of said numeral keys will shift said latch to effective position, and depression of said motor-trip key will lock said latch against shifting and thereby lock all of said numeral keys. 105
38. In combination, computing mechanism comprising numeral keys, devices in which numbers may be indexed in accordance with the numeral keys depressed, and a general operator whereby numbers so indexed may be computed, motor mechanism for actuating said general operator, a motor-trip key for controlling said motor mechanism, a pivoted latch adapted to co-operate with said motor-trip key and lock the same against actuation, and means whereby the depression of any one of said numeral keys will cause said latch to be swung into effective position, and depression of said motor-trip key will lock said latch and consequently all of said numeral keys against actuation. 110
39. In combination, computing mechanism comprising numeral keys, devices in which numbers may be indexed in accordance with the numeral keys depressed, and a general operator whereby numbers so indexed may be computed, motor mechanism for actuating said general operator, a motor-trip key for controlling said motor mechanism, a device made effective by the depression of any numeral key to prevent depression of any of the other numeral keys, and means whereby said preventing device when rendered effective by any one of said numeral keys will effect locking of said motor-trip key, and depression of said motor-trip key will render said device effective to prevent depression of any of the numeral keys. 115
40. In combination, computing mechanism comprising numeral keys, devices in which numbers may be indexed in accordance with the numeral keys depressed, and a general operator whereby numbers so indexed may be computed, motor mechanism for actuating said general operator, a motor-trip key for controlling said motor mechanism, a device made effective by the depression of any numeral key to prevent depression of any of the other numeral keys, a latch to co-operate with said motor-trip key and lock the same against actuation, and means whereby said preventing device when made effective by any one of said numeral keys will cause said latch to be shifted to effective position, and depression of said motor-trip key will lock said latch in its normal position, and thereby render said preventing device effective to prevent depression of any of said numeral keys. 120
41. In combination, computing mechanism comprising numeral keys, devices in which numbers may be indexed in accordance with the numeral keys depressed, and a general operator whereby numbers so indexed may 125

be computed, motor mechanism for actuating said general operator, a motor-trip key for controlling said motor mechanism, a latch adapted to co-operate with said motor-trip key and lock the same against actuation, means to prevent the depression of more than one numeral key at a time, comprising intruding members actuatable by said numeral keys and crowding dogs having a limited movement so that only one of said intruding members may be inserted at one time, a member shiftable by one of the end dogs, and means whereby shifting of said member due to actuation of a numeral key will effect locking of said motor-trip key, and actuation of said motor-trip key will lock said member against shifting, and thereby render said preventing means effective to prevent the depression of any of said numeral keys.

42. In combination, computing mechanism comprising numeral keys, devices in which numbers may be indexed in accordance with the numeral keys depressed, and a general operator whereby numbers so indexed may be computed, motor mechanism for actuating said general operator, a motor-trip mechanism, a device to actuate said motor-trip mechanism directly, a second device, including a key to actuate said motor-trip mechanism, a latch normally ineffective but adapted to be moved to effective position to engage said second motor-trip device and lock the same against actuation, a projection on the first motor-trip device, a lever extending from front to rear with its rear end adjacent the first motor-trip device and underlying the projection thereon, and having a projection adapted to engage said latch and actuate the same, an error key, error-key-actuated means whereby the index devices may be restored to normal condition, and means whereby depression of said error key will rock said lever to engage the projection on the first motor-trip device to prevent actuation thereof, and to shift said latch into effective position to lock the second motor-trip device.

43. In combination, computing mechanism comprising numeral keys, devices in which numbers may be indexed in accordance with the numeral keys depressed, and a general operator whereby numbers so indexed may be computed, motor mechanism for actuating said general operator, a motor-trip mechanism, a device to actuate said motor-trip mechanism directly, a second device, including a key to actuate said motor-trip mechanism, a latch normally ineffective but adapted to be moved to effective position to engage said second motor-trip device and lock the same against actuation, a projection on the first motor-trip device, a lever extending from front to rear with its rear end adjacent the first motor-trip device and under-

lying the projection thereon, and having a projection adapted to engage said latch and actuate the same, a clearance key, a clearance-sign-printing mechanism controlled by said clearance key, means whereby said latch, when moved to effective position, will lock said clearance key, an error key, error-key-actuated means whereby the index devices may be restored to normal condition, and error-key-actuated means for rocking said lever to cause the rear end thereof to engage the projection on the first motor-trip key to prevent actuation thereof, and to shift said latch to lock the second motor-trip key and the clearance key.

44. In combination, computing mechanism comprising numeral keys, devices in which numbers may be indexed in accordance with the numeral keys depressed, and a general operator whereby numbers so indexed may be computed, motor mechanism for actuating said general operator, a motor-trip mechanism, a device to actuate said motor-trip mechanism directly, a second device, including a key, to actuate said motor-trip mechanism, a latch normally ineffective but adapted to be moved to effective position to engage said second motor-trip device and lock the same against actuation, a projection on the first motor-trip device, a lever extending from front to rear with its rear end adjacent the first motor-trip device and underlying the projection thereon, and having a projection adapted to engage said latch and actuate the same, a clearance key, a clearance-sign-printing mechanism controlled by said clearance key, means whereby said latch, when moved to effective position, will lock said clearance key, a rockable member overlying the forward end of said lever, a link attached to said rockable member, a numeral-key-lock rendered effective when said link is shifted by said rockable member, an error key, and an error-key-actuated means for actuating said rockable member to effect locking of the numeral keys by means of said link and locking of the two motor-trip devices and the clearance key by means of said lever.

45. In combination, computing mechanism comprising numeral keys, devices in which numbers may be indexed in accordance with the numeral keys depressed, and a general operator whereby numbers so indexed may be computed, general-operator-actuating means including a starting key to render the same effective, an elimination key, elimination-key-controlled means whereby the index devices may be restored to normal condition, and means whereby depression of any one of said keys will lock the others against depression.

46. In combination, computing mechanism comprising numeral keys, devices in which numbers may be indexed in accordance with

- the numeral keys depressed, and a general operator whereby numbers so indexed may be computed, general-operator-actuating means including a starting key to render the same effective, an elimination key, elimination-key-controlled means whereby the index devices may be restored to normal condition, a clearance key, a clearance-sign-printing mechanism controlled by said clearance key, and means whereby depression of either a numeral key or the elimination key will lock all the other keys against depression, and depression of the starting key will lock the numeral keys and the elimination key against depression.
47. In combination, computing mechanism including numeral keys for controlling the same, a clearance key, a clearance-sign-printing mechanism, normally urged to print, a latch normally restraining said printing mechanism, means whereby said clearance key may shift said latch to ineffective position, a device shiftable to a position to block the movement of said latch, a locking device rendered effective by depression of any one of the numeral keys to lock the others against depression, and means actuated by said locking device, when the latter is rendered effective by depression of a numeral key, to shift said shiftable device to effective position.
48. In combination, computing mechanism comprising numeral keys for controlling the same, a clearance key, a clearance-sign-printing mechanism controlled by said clearance key, a device whereby depression of any one of said numeral keys will lock the others, and means whereby said locking device, when rendered effective by depression of a numeral key, will lock said clearance key against depression.
49. In combination, computing mechanism comprising numeral keys, devices in which numbers may be indexed in accordance with the numeral keys depressed, and a general operator whereby numbers so indexed may be computed, general-operator-actuating means including a starting key for rendering the same effective, a clearance key, a clearance-sign-printing mechanism controlled by said clearance key, a locking device whereby the depression of any one of the numeral keys will effect locking of the others, and means whereby actuation of said numeral-key-locking device, due to depression of one of the numeral keys, will lock said clearance key and said starting key against actuation.
50. In combination, computing mechanism comprising numeral keys, devices in which numbers may be indexed in accordance with the numeral keys depressed, and a general operator whereby numbers so indexed may be computed, an elimination key, elimination-key-actuated means whereby the index devices may be restored to normal condition, locking means whereby depression of any one of the numeral keys will lock the others, and means whereby actuation of said numeral-key-locking means, by any one of said numeral keys, will effect locking of said elimination key.
51. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of the elimination key will effect locking of the clearance key, and means whereby depression of a numeral key will effect locking of the clearance key.
52. In combination, computing mechanism comprising numeral keys, devices in which numbers may be indexed in accordance with the numeral keys depressed, a general operator whereby numbers so indexed may be computed, a clearance key, clearance-sign-printing mechanism controlled by said clearance key, an elimination key, elimination-key-controlled means whereby the index devices may be restored to normal condition, means whereby depression of the elimination key will effect locking of the clearance key, means whereby depression of a numeral key will effect locking of the clearance key, and means whereby depression of a numeral key will effect locking of said elimination key.
53. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of the elimination key will effect locking of the clearance key, means whereby depression of a numeral key will effect locking of the clearance key, and means whereby depression of said elimination key will effect locking of said numeral keys.
54. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means

whereby the index devices may be restored to normal condition, means whereby depression of the elimination key will effect locking of the clearance key, means whereby depression of a numeral key will effect locking of the clearance key, and means whereby movement of the general operator from its normal position will effect locking of said elimination key.

55. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of the elimination key will effect locking of the clearance key, means whereby depression of a numeral key will effect locking of the clearance key, means whereby depression of a numeral key will effect locking of said elimination key, and means whereby movement of the general operator from its normal position will effect locking of said elimination key.

56. In combination, computing mechanism comprising numeral keys, devices in which numbers may be indexed in accordance with the numeral keys depressed, and a general operator whereby numbers so indexed may be computed, a clearance key, a clearance-sign-printing mechanism controlled by said clearance key, an elimination key, elimination-key-controlled means whereby the index devices may be restored to normal condition, means whereby depression of the elimination key will effect locking of the clearance key, means whereby depression of a numeral key will effect locking of the clearance key, means whereby depression of said elimination key will effect locking of said numeral keys, and means whereby movement of the general operator from its normal position will effect locking of said elimination key.

57. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of a numeral key will effect locking of said clearance key, and means whereby depression of the elimination key will effect locking of the numeral keys.

58. In combination, computing mechanism comprising numeral keys, devices in which numbers may be indexed in accordance with

the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of said elimination key will effect locking of the clearance key, and means whereby depression of any one of the numeral keys will effect locking of the elimination key.

59. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of a numeral key will effect locking of said clearance key, means whereby depression of the elimination key will effect locking of the numeral keys, and means whereby movement of the general operator from its normal position will effect locking of said elimination key.

60. In combination, computing mechanism comprising numeral keys, devices in which numbers may be indexed in accordance with the numeral keys depressed, and a general operator whereby numbers so indexed may be computed, a clearance key, clearance-sign-printing mechanism controlled by said clearance key, an elimination key, elimination-key-controlled means whereby the index devices may be restored to normal condition, means whereby depression of said elimination key will effect locking of the clearance key, means whereby depression of any one of the numeral keys will effect locking of the elimination key; and means whereby movement of the general operator from its normal position will effect locking of said elimination key.

61. In combination, computing mechanism comprising numeral keys, devices in which numbers may be indexed in accordance with the numeral keys depressed, and operating means whereby numbers so indexed may be computed, an error key, error-key-actuated means whereby the index devices may be restored to normal condition, and means whereby depression of said error key will effect locking of said numeral keys and the return of said error key to normal position will effect release of said numeral keys.
